UNITED STATES PATENT OFFICE.

BASIL M. WILKERSON, OF BALTIMORE, MARYLAND.

DENTAL ENGINE.

SPECIFICATION forming part of Letters Patent No. 228,149, dated May 25, 1880.

Application filed March 4, 1879.

To all whom it may concern:

Be it known that I, BASIL M. WILKERSON, of Baltimore city, State of Maryland, have invented certain new and useful Improvements 5 in Dental Engines; and I hereby declare the same to be fully, clearly, and exactly described as follows, reference being had to the accompanying drawing, in which the device is illustrated in side elevation.

10 My invention relates to dental engines operated by means of a treadle, and designed to communicate motion to a flexible cable or rigid shaft to which a drill-point, disk, or other instrument is secured; and it consists in such 15 an engine embodying novel details of construction, whereby important results are attained, as hereinafter set forth.

With that class of engines having a rigid shaft to which the hand-piece is secured either 20 immediately or through the medium of a short flexible section of shafting, it is practically indispensable that the vertical shaft carrying the driven pulley shall be capable of a rocking motion, and for a reason that is obvious. 25 While not absolutely indispensable, this rocking feature is very important in that class of engines in which a flexible cable is used, and in either case it has heretofore been attained by pivoting the vertical shaft at or near the 30 fly-wheel bearings and maintaining it normally in a vertical position by means of a spring.

It has been found impossible heretofore, however, to hold the shaft with a reasonable 35 degree of stability while still admitting of the desired facility in rocking it. The salient feature of my invention consists in standing this shaft upon a somewhat extended base—placing it, in a word, in a condition of stable equilibrium, or in such position as when moved 40 its center of gravity is raised.

In the accompanying drawing, A is the fly-wheel, driven in the usual way by a treadle, (not shown,) and mounted upon a shaft, a, journaled in a base, B. The latter is extended upward above the shaft and terminates in a cross-piece, D, forming a T, as shown. Centrally in the cross-piece is secured a pin, b, and equidistant at either side are other pins, c' c'. 45

The vertical shaft C is secured below to a 50 saddle, c, which extends over the fly-wheel at either side and rests upon the pins c' c', which extend through slots d, formed in the saddle.

It is to be understood that the construction of the parts on the opposite side of the wheel to that shown in the drawing is identical 55 with that illustrated.

Pins d' are secured in the saddle at either side and beyond the slots d, each of which latter is formed in the arc of a circle described about the upper end of the other as a center. 60 A spring, D', is sprung under the center pin, b, and over the pins d', as shown, holding the saddle down upon the pins c'. The cap-piece E is mounted upon the upper end of the shaft C, and contains a pulley driven by a belt, e, 65 from the fly-wheel A. To the spindle of the driven pulley is attached the cable H, carrying the hand-piece I. A spring, K, is attached at one end to the cap-piece E, and is provided at the other with a ring, through which the 70 cable passes, the spring being designed to sustain the cable and prevent its fracture as the hand-piece is allowed to fall.

It will be noticed that the entire superstructure above the fly-wheel rests upon a base 75 whose area is the quadrilateral described by lines joining the pins c'. As a consequence the device is in a state of stable equilibrium until the perpendicular let fall from its center of gravity falls without this base when the 80 shaft is rocked. This rocking is somewhat resisted by the spring D', which brings the device back to a vertical position even when disturbed to the ultimate limit afforded by the slots d. As the shaft is rocked it moves upon one 85 of the pins c', and may be so rocked until the bottom of the opposite slot brings up against the other pin.

Inasmuch as the motion of the device is not about the center shaft, a, it might seem that 90 upon rocking the shaft unequal tension would be brought upon the belt e; but the peculiar disposition of the pivots c' is such that practically this is not the case.

In the drawing the heavy dotted line x represents what would be the path of the top of the pulley did it pivot upon the shaft a, and the fine dotted lines 1 2 1 3 show what is actually its path, pivoting as it does upon the pins d' d'. The variation is at its maximum at the 95 points 2 and 3, and even there it is utterly insignificant, as it amounts only to about: rad.—cos. of angle c' 1 b, as the angle is so small its radius and cosine may be considered equal, so 100

the tension of the belt is practically not affected by the rocking of the shaft. When used with a flexible shaft or cable it is not essential that the shaft shall be capable of rocking to both sides of the perpendicular, as the cable will not transmit a thrust; but the described construction is equally as convenient and more symmetrical under all circumstances.

What I claim is—

- 10 1. A dental engine having its vertical shaft mounted loosely upon the pedestal on an extended base, and being thereby in a condition of stable equilibrium, substantially as described.
- 15 2. A dental engine having its vertical shaft capable of oscillation laterally, and normally retained in a vertical position upon an ex-

tended base by means of a spring, substantially as described.

3. A dental engine having its vertical shaft 20 normally retained in a vertical position by means of a spring, and capable of oscillation laterally upon pivots located upon either side of the fly-wheel and at either side of the perpendicular through the fly-wheel shaft, as set 25 forth.

4. In combination with the fly-wheel and vertical shaft, the base-piece having pins *b c'* and the slotted saddle *c* and spring *D'*, substantially as described.

BASIL M. WILKERSON.
